VACUUM PUMP

Morris Barnett, San Francisco, Calif., assignor to
David B. Webb, Alamo, Calif.

Filed Apr. 22, 1968, Ser. No. 11,566

Term of patent 14 years

Int. Cl. D15—02

U.S. Cl. D65—1

Fig. 3.

Fig. 4.

Fig. 6.

Fig. 7.

FIGURE 1 is a front elevational view of a vacuum pump showing my new design.

FIGURE 2 is a rear elevational view thereof;

FIGURE 3 is a first side elevational view thereof;

FIGURE 4 is a reverse side elevational view thereof;

FIGURE 5 is a top plan view thereof;

FIGURE 6 is a bottom plan view thereof;

FIGURE 7 is a perspective view in enlarged scale thereof.

I claim:

The ornamental design for a vacuum pump, as shown and described.
